CATHODE RAY TUBE GUN STRUCTURE

William E. Bradley, New Hope, Pa., assignor to Philco Corporation, Philadelphia, Pa., a corporation of Pennsylvania

Application October 9, 1952, Serial No. 313,907

16 Claims. (Cl. 313—82)

The present invention relates to electron discharge devices and more particularly to improved electron beam generating assemblies for cathode-ray tubes.

The invention is particularly applicable to cathode-ray tubes for producing television images, in which use the small spot size and large current values of the electron beam produced by the assembly of the invention brings about important improvements in the reproduced detail and the brightness of the televised image. While the invention will be specifically described in this connection, it should be well understood that the invention is also applicable to other forms of cathode-ray tubes requiring an electron beam having a small spot size and/or a large current capacity.

One of the factors determining the amount of image detail reproducible by the fluorescent screen of a cathode-ray television tube is the cross-sectional area of the spot formed by the cathode-ray beam at its point of impingement on the screen surface. In order to achieve the maximum detail derivable from the image signal applied to the tube, the beam spot must be relatively small.

It has been proposed to reduce the size of the beam spot by reducing the effective emission area of the cathode of the beam generating system—for example, by the use of a masking electrode having a small aperture and arranged along the path of the electron stream. However, it is found that this expedient correspondingly reduces the beam current so this expedient correspondingly reduces the beam current so that the brightness of the image produced at the screen of the cathode-ray tube is adversely affected to the extent that it is not visually acceptable. While the beam current may in turn be increased by operating the cathode at large emission current densities, this remedy is impracticable because the life of the cathode is shortened prohibitively.

It is an object of the invention to provide an improved cathode-ray tube assembly adapted to produce an electron beam having a small spot size.

A further object of the invention is to provide an improved cathode-ray tube system adapted to produce a beam having a small spot size and a large current capacity without subjecting the source of the beam to large emission current densities.

Another object of the invention is to provide an improved cathode-ray tube beam generating system which is simple to manufacture and of low cost, and which may readily be made within close precision tolerances.

Further objects of the invention will appear as the specification progresses.

In accordance with the invention the foregoing objects are achieved by constructing the cathode emission surface of the beam generating system with a configuration which insures that, at any point of the effective cathode surface, the electrons are emitted in a direction so correlated to the emission direction over the remainder of the cathode surface, and to the accelerating electric field at the cathode surface, that all of the emitted electrons are caused to

2

focus at substantially the same point along the axis of the electron optical system formed by the cathode and by the intensity control electrode of the system.

More specifically in accordance with the invention, a beam generating and intensity control system is provided in which the peripheral portions of the effective emission area of the cathode exhibit a convex contour relative to the contour of the central portion of the emission area so that electrons emitted at the peripheral and central portions are made to converge substantially at the same point along the axis of the system.

As a further feature of the invention, the cathode and beam intensity control electrode are constructed with a spacing and a configuration which establish, over a major portion of the effective emission surface of the cathode, a region of intense voltage gradient, and equipotential lines which are substantially parallel to the surface of the cathode, and which insures that the emission paths of the electrons conform to a pattern as established by the aforementioned shaping of the emission surface.

The invention will be described in greater detail with reference to the appended drawings forming part of the specification and in which:

Figure 1 is a plan view, partially in cross-section, showing a cathode-ray tube embodying the novel beam generating assembly of the invention;

Figure 2 is a cross-sectional view of one form of a beam generating assembly in accordance with the invention;

Figure 3 is a plan view of the assembly of Figure 2;

Figure 4 is a cross-sectional view, on an enlarged scale, showing details of the beam generating assembly of the invention in accordance with one embodiment thereof;

Figure 5 is a cross-sectional view, on an enlarged scale, showing details of another embodiment of the invention; and

Figure 6 is a cross-sectional view, on an enlarged scale, showing details of a further embodiment of the invention.

Referring to Figure 1, the cathode-ray tube shown therein comprises an evacuated envelope 10 of well known form consisting for example of glass. Within the envelope 10 there are arranged a beam generating and controlling system 12 in accordance with the invention and later to be more fully described, a focusing electrode 14, and a beam accelerating electrode 16 which may consist of a conductive coating on the inner wall of the envelope in conformity with well established practice.

The end face 18 of the envelope 10 may be provided with a beam intercepting structure, the actual construction of which is determined by the particular function which the cathode-ray tube is to serve. In one instance, for example, the cathode-ray tube may be used for producing a color television image in a system of the type disclosed in the copending application of Melvin E. Partin, Serial No. 242,264, filed August 17, 1951, in which case the beam intercepting structure arranged at the faceplate may comprise consecutively arranged groups of phosphor stripes, the stripes of each of the groups being adapted to produce light of three different primary colors upon electron impingement. In such an arrangement, the beam intercepting structure may further comprise index signal generating portions having a geometric configuration indicative of the geometric configuration of the phosphor stripes and adapted to produce an appropriate indexing signal upon electron impingement. A beam intercepting screen structure of the foregoing type has been described in detail in the above-mentioned Partin application and a further description thereof in the present application is believed to be unnecessary.

As disclosed in the said Partin application, the beam intercepting structure is energized by an electron beam generating and control system adapted to produce two

separate electron beams individually controllable in intensity. One of the beams serves to energize the image producing phosphor stripes, whereas the other beam serves to energize the indexing portions of the screen to produce an output signal indicative of the position of the beams.

The assembly of the invention is particularly suitable for a dual beam generating and control system for the above indicated purpose, and will be described with specific reference to such a system. However, it should be well understood that the invention is equally applicable to single beam systems and brings about important improvements in the spot size and beam current characteristics of such systems.

A dual beam generating and control system is shown in Figures 2 and 3. The assembly shown, which may be of the general form described and claimed in the copending application of W. L. Fite et al., Serial No. 307,868 filed September 4, 1952, comprises a cylindrical member 20 having a tubular body portion 22 extending into an annular end portion 24. The portion 24 may be formed as a separate element and thereafter suitably secured—by welding, brazing or the like—to the body portion 22, but is preferably formed as an integral portion of the body portion 22, for example by extrusion. Portions 22 and 24 may consist of nickel, stainless steel, or of other suitable material commonly used in the manufacture of gun assemblies for cathode-ray tubes. At the junction of the body and end portions 22 and 24, the tubular portion 22 is provided with peripheral slots 26 and 28.

Within the sleeve 20 are two intensity control electrodes 34 and 36, each in the form of a spade element extending through one of the peripheral slots 26 and 28 towards the central axis of the sleeve 20. At their inner portions adjacent to the axis of sleeve 20, electrodes 34 and 36 are each provided with an aperture, shown as 38 and 40 respectively, through which pass the respective beams to be individually controlled. The apertures 38 and 40, later to be more fully described, may be of equal dimensions in the event that identical beams are to be formed, or may be of different dimensions where non-similar beams are desired.

Electrodes 34 and 36 are rigidly supported, in an electrically insulated manner, within the sleeve 20 by means of electrically insulating washers 42 and 44 and by means of a flanged metal ring 46 which may be welded to the inner surface of the sleeve 20. As will be noted, washer 42 is interposed between the electrodes 34—36 and the annular end portion 24, whereas washer 44 is arranged between the said electrodes and the ring 46. By adjusting the compression exerted by the ring 46 against the washer 44, the control electrodes 34 and 36 may be securely positioned within the sleeve 20. The adjustment by the ring 46 is preferably effected after precisely aligning the electrodes so that the apertures 38 and 40 thereof are arranged on a common diameter and the abutting surfaces of the electrodes form a uniform gap 48 having a width of the order of .002" which has been found to be sufficiently small to establish an electrostatic field sufficient to prevent electrons from passing through the gap under normal operating conditions of the cathode-ray tube.

In practice, the insulating washers 42 and 44 consist of mica; however, it will be apparent that other suitable stable insulating materials such as ceramic materials may be used.

Also positioned within the sleeve 20 is a cathode assembly 50 which may consist of a nickel or stainless steel sleeve 52 open at the bottom end thereof and closed at the top end by a nickel cap 54 to provide a suitable base for an electron emissive coating 56. Coating 56 may be of conventional composition and may consist, for example, of a mixture of barium and strontium oxides.

The cathode assembly 50 is secured within the sleeve 20 by means of an apertured ceramic disc 58 to which

the assembly 30 is affixed by headings 60 and 62 formed on the periphery of the sleeve 52. For locating the disc 58 within the sleeve 20 there are provided an annular spacer 64 consisting of an insulating material—for example, a ceramic, such as steatite, lavite or the like—one end of which abuts the exposed surface of the mica washer 44 and the other end of which abuts the top surface of the disc 58, and a metal flanged ring 66 which abuts the lower surface of the disc 58 and is welded or otherwise secured to the inner surface of the sleeve 20.

In order to position the electrodes 34 and 36 in a common plane and at a fixed predetermined distance from the surface of the electron emitting coating 56, insulating spacers 42 and 44 are formed with substantially flat parallel surfaces and the spacing determining elements are formed to precisely controlled dimensions. This may be most simply effected by the use of mica for the spacers 42 and 44, as above pointed out, since this material splits with substantially parallel surfaces and can be accurately controlled as to its thickness, and by grinding the active surfaces of the spacer 64 and the disc 50.

Desirably the beams emanating from the apertures 38 and 40 are made to converge so that the two beams pass through the same part of the field serving to deflect them throughout the image area. In the arrangement shown in Figure 2, this is effected by means of a converging electrode 68 in the form of an annular metal disc interposed between the insulating washer 42 and the end portion 24 of the member 20. The degree of convergence imparted to the beams may be controlled by adjusting the diameter of the aperture of electrode 68, the spacing between the electrode 68 and electrodes 34—36, and the potential applied to the electrode 68, whereby, the smaller the diameter of the aperture of electrode 68 and/or the greater the spacing between electrode 68 and electrodes 34—36 and/or the less positive the potential of electrode 68, the greater will be the convergence produced by electrode 68. In the arrangement shown, electrode 68 is electrically insulated from the member 20 by means of an insulating washer 70, for example of mica, interposed between electrode 68 and the end portion 24. While the electrode may thus be operated at a potential different from that of sleeve 20 or of the remaining components contained within sleeve 20, in practice the electrode 68 is operated at the same potential as sleeve 20, in which case the insulating washer 70 may be omitted.

A suitable electrical heater (not shown) of well known form may be enclosed within the cathode sleeve 52 to maintain the emissive coating 56 thereof at its electron emitting temperature.

Electrical connection to the cathode sleeve 52 may be provided by a tab 72 welded thereto, whereas individual electrical connections to the electrodes 34 and 36 may be provided by tab extension portions 74 and 76 respectively of these electrodes. An individual connection to the electrode 68 may be provided by a tab extension portion 78 extending through a peripheral aperture 80 of the sleeve 21. In practice, the sleeve 20 may be operated at cathode potential, and for this purpose it may be provided with a tab connection 82.

The assembly may be supported within the tube envelope by means of supporting ears 84 which are fused to glass rods 86 (see Figure 1) which similarly support the focusing anode 14, and by means of wire standards serving as the connecting elements for the electrodes.

The assembly may be centered within the neck of the cathode-ray tube envelope 10 by a ribbed disc 88 which is welded to the anode 14 and the ribs of which bear against the inner wall of the neck of the envelope.

In accordance with the invention, an electron beam having a small spot size and large current capacity is achieved by constructing the cathode emission surface with a configuration which insures that, at any point of the effective cathode surface, the electrons are emitted in a direction so correlated to the emission direction over the remainder of the cathode surface that all of the

electrons are focused at substantially the same point along the axis of the electron-optical system formed by the cathode and by the intensity control electrode of the system.

More particularly, and in accordance with the embodiment of the invention shown in Figure 4, the peripheral portion of the effective emission area of the cathode is made progressively more convex as a function of the distance from the center of the area so that the electrons which are emitted by the peripheral portions, and which normally focus at a point relatively close to the cathode surface, are made to focus at a point which is further along the axis and thus at a point substantially coincident with the focus point of the centrally emitted electrons. More specifically, and as will be noted from Figure 4, an electron emissive coating 100 which is arranged on a base 102, and which has an effective surface 101 as defined by the projected area of the aperture 104 of an intensity control electrode 106, is shaped so that the peripheral portions 108 of the area 101 have a convex configuration, whereas the central portion 110 of the area 101 is substantially planar and parallel to the plane of the confronting surface of the electrode 106.

By forming the peripheral portions 108 with a convex surface, electrons emitted by these portions are made to assume an off-axial velocity so that, in the subsequent acceleration thereof normally produced by the accelerating voltage gradient at the cathode surface, these electrons are made to cross the axis of the system at a more remote position from the cathode surface than would otherwise occur if the cathode surface was not made with such a configuration. Since the central portion 110 of the emission area is planar, the electrons emitted thereby are not correspondingly influenced to any substantial degree so that these electrons focus at their normal point along the system axis.

The extent of the convex area 108 is determined by the dimensions and shape of the area 101, and by the distribution of the equipotential lines at the emissive surface. In practice, in the case of a circular emission area as defined by a circular aperture 104, the limits of the convex boundary area as defined by the dimension *a* in Figure 4 preferably do not exceed about 50% of the radius *r* of the emission area.

In order to achieve maximum utilization of the benefits derived by the compound surface configuration of the emission area as shown in Figure 4, it is desirable to construct the cathode-control electrode system so that the equipotential lines of the accelerating field are substantially parallel to the major portion of the surface of the emission area 101 and preferably a large voltage gradient is produced at the emission surface. To achieve this, the preferred system of the invention is further characterized by a relatively small spacing between the effective plane of the surface of the emission area and the plane of the confronting surface of the control electrode relative to the diameter of the emission area. For example, the spacing between cathode and control electrode surfaces may be of the order of .0015 to .005" when the diameter of the aperture 104 is of the order of .015". Furthermore, since the intensity of the voltage gradient at the emission surface and the distribution of the equipotential lines are further influenced by the thickness of the control electrode 106—whereby, in general, the greater the thickness of the control electrode, the smaller the effective size of the aperture and hence the smaller the average voltage gradient and the more curved the contours of the equipotential lines—the size of the aperture 104 is preferably effectively increased by chamfering the edges of electrode 106 which define it, as shown at 112. Since, for a given aperture size and a given thickness of the electrode 106, the chamfer angle determines the effective area of the aperture, the angle should be as large as possible consistent with good heat conductivity at the edges of the aperture. In practice, the chamfer angle θ may have a value between about 30° and about 60°, 75

and, for a control electrode .005" thick and an aperture 104 having the dimensions above noted, the angle θ may have a value at 45°.

Instead of constructing the cathode surface so that electrons emitted at the peripheral portions of the emission area are made to converge at a point more remote than normal from the cathode surface, the desired coincidence of the focus point of the centrally and peripherally emitted electrons may be effected by shortening the focal distance of the centrally emitted electrons. This may be achieved by the arrangement shown in Figure 5 wherein an emissive layer 120 arranged on a base 122, and having an effective emission area 121 as defined by a circular aperture 124 of a control electrode 126, is formed with a concave configuration at the central portion of the emission area as shown at 128 and a planar peripheral portion as shown at 129. The degree of curvature of the surface 128 and its extent are determined by the configuration and operating characteristics of the lens system formed by the cathode 120—122 and the control electrode 126. Particularly improved results have been obtained when the concave surface 128 is spherical with a radius of curvature within the range of $\pm 20\%$ of the distance between the desired focus point and the surface of the cathode, and when the surface 128 is restricted so that the dimension *c* thereof does not exceed about 60% of radius *r* of the emission area 121. The construction shown in Figure 5 operates to impart to the electrons emitted by the central portion of the surface 121 an inward radial velocity causing these electrons to focus at a point on the axis closer to the cathode surface than would normally occur. By this shortening of the focus distance, the focus point of the centrally emitted electrons is made to coincide substantially with the focus point of the peripherally emitted electrons.

Figure 6 illustrates a further modification of the contour of the emission area in accordance with the invention. In Figure 6, an emission layer 130 applied to a base 132, and having an effective emission area 131 as defined by a circular aperture 134 of an intensity control electrode 136, is formed with a convex contour at the peripheral portions as shown at 138 and with a concave contour at the central portion as shown as 140. As in the case of the constructions shown in Figures 4 and 5, the degree and extent *d* and *e* of the curvatures of the surfaces 138 and 140 are determined by the configuration and operating characteristics of the electron lens formed by the cathode 130—132 and the control electrode 136, and by the desired diminution of the size of the beam spot produced. The limits of curvature and the extent thereof described in connection with Figures 4 and 5 apply equally to the convex-concave surface shown in Figure 6.

The construction shown in Figure 6, by means of which the focal distance of the peripherally emitted electrons is lengthened and the focal distance of the centrally emitted electrons is shortened to a common coincidence point, brings about beams having extremely small spot sizes. Such small spot beams are particularly desirable for small size camera tubes for television and for color television image reproducers in which the image screen is in the form of a plurality of adjacently positioned thin phosphor stripes, as above described, or in the form of a plurality of phosphor dots. In such color image reproducing tubes the beam spot should be smaller than the area of the phosphor deposit to prevent desaturation of the colors of the reproduced image.

While I have described my invention by means of specific examples and in a specific embodiment, I do not wish to be limited thereto for obvious modifications will occur to those skilled in the art without departing from the spirit and scope of the invention.

What I claim is:

1. A cathode-ray tube assembly comprising an evacuated envelope and within said envelope an electron beam generating and intensity control system and a beam intercepting member arranged in spaced relationship to said

beam generating and control system, said beam generating and control system comprising a cathode electrode and a control electrode arranged in spaced and directly confronting relationship to said cathode and being provided with an aperture, said aperture defining an effective emission area of said cathode and said control electrode being adapted to control the flow of electrons from said effective emission area, said emission area having a surface configuration, a portion of which has a given curvature in a given direction and another portion of which has a curvature in said given direction less than said given curvature, and means for producing at said effective emission area a voltage gradient to accelerate electrons from said emission area through said aperture.

2. A cathode-ray tube assembly as claimed in claim 1 wherein said peripheral portion of said effective emission area has a convex configuration.

3. A cathode-ray tube assembly as claimed in claim 2 wherein the said effective emission area is substantially circular and wherein the said peripheral portion of convex configuration is limited to a radial distance from the center of said emission area greater than about 50% of the radius of the said emission area.

4. A cathode-ray tube assembly as claimed in claim 1 wherein said central portion of said effective emission area has a concave configuration.

5. A cathode-ray tube assembly as claimed in claim 4 wherein the said effective emission area is substantially circular and wherein said central portion of concave configuration is limited to a radial distance from the center of the said emission area to a value less than about 60% of the radius of the said emission area.

6. A cathode-ray tube assembly as claimed in claim 4 wherein said central and peripheral portions of the said effective emission area are so configured that the electrons emitted therefrom have substantially coincident focal points and wherein the radius of curvature of the concave central portion has a value within about $\pm 20\%$ of the distance between said focal points and the surface of said emission area.

7. A cathode-ray tube assembly as claimed in claim 1 wherein said peripheral portion of said effective emission area has a convex configuration and wherein said central portion of said emission area has a planar configuration substantially parallel to the confronting surface of said control electrode.

8. A cathode-ray tube assembly as claimed in claim 1 wherein said central portion of said effective emission area has a concave configuration and wherein said peripheral portion of said emission area has a planar configuration substantially parallel to the confronting surface of said control electrode.

9. A cathode-ray tube assembly as claimed in claim 1 wherein said central portion of said effective emission area has a concave configuration and wherein said peripheral portion of said emission area has a convex configuration.

10. A cathode-ray tube assembly as claimed in claim 9 wherein the said effective emission area is substantially circular, wherein said concave central portion thereof extends to a radial distance less than about 60% of the radius of said circular area, and wherein said convex peripheral portion thereof extends from a distance more than about 50% of the said radius from the center of said circular area.

11. A cathode-ray tube assembly as claimed in claim 1 wherein said aperture has linear dimensions so proportioned relative to the spacing between said cathode and said control electrode that the field produced at said emission surface exhibits equipotential lines substantially parallel to the emission area over substantially the entire surface thereof projected through said aperture.

12. A cathode-ray tube assembly as claimed in claim 11 wherein said aperture has a chamfered opening the angle

of the chamfer of which has a value between 30° and 60°.

13. A cathode-ray tube assembly for producing two electron beams individually controllable in intensity, comprising a tubular metal member having a cylindrical body portion and a flange portion provided with a central aperture and secured to one end of said body portion, said body portion, at the portion thereof adjacent to said flange portion, being provided with two diametrically disposed peripheral apertures, first and second beam intensity control electrodes, each having a planar active portion and a planar body portion, said active portions being arranged in juxtaposition and the body portions of said electrodes being arranged substantially in parallel planes and extending through said peripheral apertures, a first electrically insulating member having a central aperture and being secured between said flange portion and one side of said body portions of said electrodes, a second electrically insulating member having a central aperture, means to secure said second insulating member in contact with the other side of the body portions of said electrodes, each of said active portions of said electrodes being provided with an aperture, a cathode assembly having a cylindrical body portion and an end portion, electron emissive material disposed on said last mentioned end portion and forming active surfaces thereon within areas defined by the projections of the respective apertures of said electrodes on said last mentioned end portion, one of said active surfaces having a surface configuration, a portion of which has a given curvature in a given direction with respect to said last mentioned end portion and another portion of which has a curvature in said given direction less than said curvature, and means adapted to produce at said active surfaces a voltage gradient for accelerating electrons from said active areas through said apertures of said active portions of said electrodes.

14. A cathode-ray tube assembly as claimed in claim 13 further comprising an annular electrode member interposed between said first electrically insulating member and said flange portion and adapted to converge electrons accelerated through one of said apertured active portions toward electrons accelerated through the other of said apertured active portions.

15. A cathode-ray tube assembly comprising an evacuated envelope, an electron beam generating and intensity control system within said envelope, and a beam intercepting member within said envelope arranged in spaced relationship to said beam generating and control system, said beam generating and control system comprising a cathode and an intensity control electrode adjacent thereto, said intensity control electrode having an aperture therein and being spaced from said cathode, said aperture defining an effective emission area of said cathode, said effective emission area having a central portion and a peripheral portion, said peripheral portion having a surface contour which is convex relative to the contour of said central portion, said contours being respectively constructed so that substantially all the electrons emitted therefrom are focussed at a common focal point, and means for producing at said effective emission area a voltage gradient to accelerate said emitted electrons through said aperture.

16. A cathode-ray tube assembly comprising an evacuated envelope, an electron beam generating and intensity control system within said envelope, and a beam intercepting member within said envelope arranged in spaced relationship to said beam generating and control system, said beam generating and control system comprising a cathode and an intensity control electrode adjacent thereto, said intensity control electrode having an aperture therein and being spaced from said cathode, said aperture defining an effective emission area of said cathode, said emission area having a surface configuration the peripheral portion of which has a given curvature in a given direction and the central portion of which has

a curvature in said given direction less than said given curvature.
